UNITED STATES PATENT OFFICE.

EMIL BOMMER, OF BROOKLYN, NEW YORK.

SPRING-HINGE.

1,241,081.

Specification of Letters Patent. Patented Sept. 25, 1917.

Application filed May 2, 1914. Serial No. 835,888.

To all whom it may concern:

Be it known that I, EMIL BOMMER, a citizen of the United States of America, and a resident of the borough of Brooklyn, 5 county of Kings, city and State of New York, have invented certain new and useful Improvements in Spring-Hinges, of which the following is a specification.

This invention relates to spring-hinges, 10 and more particularly to those types respectively known as vertical-type floor-surface spring-hinges, and horizontal-type floor-surface spring-hinges, and has for its object to provide extraneous means for locking 15 the spring-action on the hinge into inoperative position when it is desired to use the door without the spring-action, until such time as the door is required to again have the spring-action restored thereto, 20 which is effected by withdrawing said extraneous means.

The invention is shown in various embodiments in the drawings and will be more fully described hereinafter and finally 25 pointed out in the claims.

In the accompanying drawings:

Figure 1 is a side view of a vertical type of floor-surface spring-hinge embodying my invention,

Fig. 2 is an end view thereof locked into inoperative position, so as to enable the door to be used without the operation of the spring-action of the hinge.

Fig. 3 is a plan view of the invention applied to a different form of hinge known as the horizontal type of floor-surface spring-hinge.

Fig. 4 is a side view showing my invention applied to a different form of a vertical 40 type of floor-surface spring-hinge.

Fig. 5 is an end view of the same,

Fig. 6 is a side view of the embodiment shown in Fig. 4 with the parts locked into inoperative position so as to enable the door 45 to be used without the operation of the spring action of the hinge.

Fig. 7 is another embodiment of the same invention, and

Fig. 8 is still another embodiment.

Similar characters of reference indicate corresponding parts throughout the various figures.

Referring to the drawings, and more particularly to Fig. 1, one form of the vertical type of floor-surface spring-hinge is 55 shown therein, the essential parts of which

are described and claimed in my copending application filed April 15, 1913, under Serial No. 761,140, to which reference is hereby made. The parts thereof consist of 60 a hinge-frame 10 in which a spindle 11 is journaled; the spindle 11 having a squared lower end 12 non-rotatably seated in a floor-plate 13, which is secured to the floor by screws 14. The spindle 11 is provided with 65 a lower spring-holder 15 and an upper adjustable spring-holder 16; said adjustable spring-holder 16 has a tension collar 16^a in conjunction therewith; the spring-holder 15 and tension-collar 16^a have interior and 70 exterior projections or lugs, the exterior projections or lugs 17 and 18 each having one beveled face and one vertical face. Intermediate the spring-holders 15 and 16, and connecting therewith, a coil-spring 19 75 is arranged. At the side of the frame 10, a locking mechanism is arranged which is provided with projections 21 and 22, which engage the vertical-faces 23 and 24 of the beveled lugs 17 and 18, but which projections 22 and 21 may be moved out of the path of the vertical faces, so as to be released therefrom, so as to pass over the beveled-faces of the projections or lugs 17 and 18. When so moved out of contact with 80 the vertical faces of these projections 17 and 18, the spring-action is disengaged from the hinge-frame and the door may be opened and will remain open without any spring-action until the door is again closed, which 85 act of closing the door automatically restores the spring-action to the door.

In order to lock this mechanism into a position so as to retain the spring-action of the spring-hinge in disengaged or inoperative position, so that the door can be freely operated in either direction beyond the closed position without any spring-action, the frame 10 and side-plates 40 are provided with an opening 25, through which a rod 100 25^a or nail, etc., is passed or inserted under the locking mechanism 26 when said locking mechanism is in raised position and the lugs 21 and 22 are out of engagement with the vertical faces 23 and 24. This nail or rod 25^a holds these parts in inactive position, and thereby the door may be opened or closed or moved into any position without any action of the spring, until the said nail or rod 25^a is withdrawn.

In Fig. 3 another embodiment is shown, which shows the horizontal type of floor-

surface spring-hinge, and which consists of a hinge-frame 39 having guide-plates 39^a, said hinge-frame 39 being fastened to a door 49 and being journaled on a stationary-member 43 of the hinge, said stationary member 43 having spaced vertical rollers 35 and 36, the member 43 being socketed, as shown at 43^a to a floor-plate 46 which is fastened to the floor 48 by screws 47 or other means, 10 a bearing-member 33 having a face 37 to engage the vertical rollers 35 and 36, a lug 37^a preferably on its lower side and disk rollers 39^b at its upper and lower sides, an extension-rod 30 on the bearing-member 33, 15 a coiled spring 31 on said rod, the bearing-member 33 and its rod 30 being respectively guided to forward and backward movement within the hinge-frame by rollers 39^b between the guide-plates 39^a of the hinge-frame and in a perforation 30^a of the hinge-frame 39. The door casing 44 is shown in cross section. The side-plates are shown at 40.

When it is desired to disengage the spring-action from the door, the door is opened to either side or direction (shown in Fig. 3 opened in one direction), whereby the spring 31 is compressed until the bearing member 37 is pushed beyond the ends of the guide-plates 39^a sufficiently to permit the insertion of a nail, or piece of wire 38 between the lug 37^a and the ends 39^c of the guide-plate 39^a, or the nail or piece of wire may be inserted in perforations 39^c of the guide-plates 39, thereby locking the coil-spring 31 into inoperative position as shown in Fig. 3; by this means the face 37 of the bearing-member 33 is maintained out of contact with the rollers 35 and 36, and thereby the door 40 may be moved independently of the action 45 of the spring. The spring action may at any time be restored to the door by again opening the door at either side as shown in Fig. 3, and withdrawing the nail or wire 38.

45 In Figs. 4, 5, 6, 7 and 8 still another embodiment of the vertical-type of floor-surface spring-hinge is shown. This type of hinge differs essentially from the embodiment heretofore described and shown in Figs. 1 and 2, which has the spindle rigidly and non-rotatably socketed in the squared or non-circular socket of a floor-plate by means of the correspondingly square-shaped or non-circular end of the spindle, whereas, 50 in the type shown in Figs. 4, 5, 6, 7 and 8, the spindle may be disconnected from the floor-plate so as to rotate in the floor-plate without spring-action when the door is to be held open. In Fig. 4, 80 represents the door, 81 represents the floor; the spindle 60 has a downward projection 61, which is journaled in the floor-plate 62. The spring-holder 63 with its spring 64 is arranged in the usual well known manner, and the spindle 60 is provided with an enlarged flange 65, which has a cut-out portion 66 therein.

In the frame 67 of this type of spring-hinge is arranged a vertically-movable spring-actuated pawl or detent 68, which projects out of the frame with its nose-piece 69 and operates upon and contacts with a vertically-movable spring-actuated cylindrical-member or plug 70 which is normally retained in its upper position by means of the spring 71 which is fastened to the floor-plate by the screw 72. This vertically movable cylindrical-member or plug 70 of the floor-plate 62 normally engages the opening 66 of the enlarged-flange 65 of the spindle under the upward pressure of the spring 71, and while it so engages it, the spindle 60 is connected to the floor-plate 62 and the spring-action is in engagement to close the door when same is operated. If, however, it is desired to hold the door open without the action of the spring, the detent 69 is pushed downward and forces the vertically-movable cylindrical-member or plug 70 downward below the enlarged-flange 65 of the spindle 60, and permits thereby the spindle 60, together with the hinge-frame 67, to rotate in the floor-plate 62, and the flange 65 to pass over the vertically-movable cylindrical-member or plug 70 without engaging therewith while the door is open; when, however, the door is again brought to closed position, the vertically movable cylindrical-member or plug 70 under the action of the spring 71 is again brought into connection with the flange 65 of spindle 60, and the spring-action is there-by automatically restored to the door. This is clearly shown in Fig. 6.

In order to lock the spring-action in disengaged position when it is desired to freely operate the door in either direction without the spring-action of the spring, the frame 67 and side-plate 40 are provided with an opening 73, through which a nail 74 or piece of wire or similar obstruction is inserted, which also passes through a corresponding opening 75 in the detent 68. By this passing through of these parts, the detent is locked in its downward position, thereby preventing the vertically movable, cylindrical plug 70 from again connecting with the flange 65 of the spindle 60 until said nail 74 or other similar obstruction is withdrawn from the opening 73 of the frame 67 for the purpose of again restoring the spring-action of the spring to the hinge. This is clearly shown in Figs. 5 and 6.

A modified form of this device is shown in Fig. 7, in which the frame is provided with an opening 76, and with a detent with a cut-out portion 77, which portion is locked by the nail, or rod described.

Another embodiment of my invention is shown in Fig. 8, in which the vertically-movable cylindrical-member or plug 70 is provided with a groove 78, which groove,

when it is in registration with an opening 79 of the door-plate 62 permits a nail or piece of wire as that described to be passed therethrough and to lock the cylindrical member 70 in its downward position. By this locking action, the member 70 is held in its downward position and out of connection with the cut-out portion 66 of the enlarged flange 65 of the spindle 60 while the door is desired to be operated without any spring-action of the spring, and the spring-action may be restored to the door at any time by withdrawing said nail or piece of wire or rod.

15 In the embodiments described, where necessary or desirable, a suitable hole corresponding to the location of the hole in the hinge-frame can be made in the side-plates 40 so that the extraneous means as a wire, 20 nail, or rod, etc., may be inserted without unscrewing the side-plates.

25 I have described several embodiments of my invention, but it is clear that changes may be made therein without departing from the spirit of the invention as defined in the appended claims.

I claim:

1. In a spring hinge, the combination of a hinge frame, a spring control element 30 comprising a spindle and a spring actuated member carried thereby, and rotatable with respect thereto during spring action of the door, means adapted to be moved with respect to the said spring control element to 35 make the spring action thereof inactive with respect to the door, a casing inclosing said hinge, said casing and said first named means being provided with registering passages in the inactive position of said spring 40 control element forming an uninterrupted passage through the hinge, and independent means separate and detached from said hinge adapted to be engaged with said registering passages from either side of the 45 door to retain said first named means in said moved position until said independent means is removed, said casing forming an immovable support at each side of the hinge for said independent means.

50 2. In a spring hinge, the combination of

a hinge frame, a spring control element comprising a spindle and a spring actuated member carried thereby and rotatable with respect thereto during spring action of the door, means adapted to be moved with respect to said spring control element to make the spring action thereof inactive with respect to the door, said means normally adapted to return to its original position upon the closing of the door, a casing inclosing said hinge, said casing and said first named means being provided with registering passages in the inactive position of said spring control element forming an uninterrupted passage through the hinge, and 60 independent means separate and detached from said hinge adapted to be engaged with said registering passages to retain said first named means in the said moved position until said independent means is removed, 65 said casing forming an immovable support at each side of the hinge for said independent means.

3. In a spring hinge, the combination of a hinge frame, a spring control element comprising a spindle and a spring actuated member carried thereby and rotatable with respect thereto during spring action of the door, means adapted to engage the spring control element to establish connection between the same and the door, means adapted to be operated to disengage said first named means from said spring control element, a casing for said hinge, said casing and said disengaging means being provided with registering means in the inactive position of said spring control element, and independent means separate and detached from said hinge, adapted to engage said registering means to retain said disengaging means in 80 disengaging position until said independent means is removed.

In testimony, that I claim the foregoing as my invention, I have signed my name in presence of two subscribing witnesses.

EMIL BOMMER.
